UNITED STATES PATENT OFFICE

171,272

DESK TRAY

William James Bargen, Waukegan, Ill.

Application March 24, 1953, Serial No. 24,187

Term of patent 14 years

(Cl. D74—5(6))

To all whom it may concern:

Be it known that I, William James Bargen, a citizen of the United States of America, residing at Waukegan, in the county of Lake and State of Illinois, have invented a new, original, and ornamental Design for a Desk Tray, of which the following is a specification, reference being had to the accompanying drawing, forming a part thereof.

In the drawing:

I claim:

The ornamental design for a desk tray, as shown.

WILLIAM JAMES BARGEN.
